UNITED STATES PATENT OFFICE.

WALTER A. OLIVE, OF INDIANOLA, IOWA.

DESIGN FOR A PENCIL-HOLDER.

49,931.

Specification for Design.

Patented Nov. 21, 1916.

Application filed February 16, 1916. Serial No. 78,772. Term of patent 3½ years.

To all whom it may concern:

Be it known that I, WALTER A. OLIVE, citizen of the United States of America, and resident of Indianola, Warren county, Iowa, have invented a new, original, and ornamental Design for a Pencil-Holder, of which the following is a specification.

The object of this invention is to provide a new and ornamental design for a pocket pencil holder.

My invention consists in the new and ornamental design for a pencil holder as shown by the accompanying drawing, in which—

Figure 1 is a front view of the pencil holder illustrating my new design, and Fig. 2 is an edge view of the same.

I claim:

The ornamental design for a pencil holder, as shown.

WALTER A. OLIVE.
